UNITED STATES PATENT OFFICE

OTTMAR WAHL, OF LEVERKUSEN, GERMANY, ASSIGNOR TO GENERAL ANILINE WORKS, INC., OF NEW YORK, N. Y., A CORPORATION OF DELAWARE

DYESTUFF DERIVED FROM INDOLINE BASES AND PROCESS OF PREPARING SAME

No Drawing. Original No. 1,755,678, dated April 22, 1930, Serial No. 186,829, filed April 26, 1927.
Application for reissue filed February 20, 1932. Serial No. 594,383.

The present invention relates to new dyestuffs derived from indoline bases and a process of preparing same.

I have found that by treating a 1.3.3-tri-
5 alkyl-2-methylene indoline (such as 1.3.3-tri-
methyl-2-methylene indoline) of the formula-
la:

15 wherein the benzene nucleus may be substi-
tuted or not or a salt thereof of the formula:

25 wherein the benzene nucleus may be substi-
tuted or not and 'x' stands for an organic or
inorganic acid radicle with an ester or a salt
of nitrous acid in the presence of an organic
acid anhydride, as for example acetic anhy-
dride which serves as a condensing agent,
there are produced new yellow to orange-red
30 dyestuffs, which correspond probably to the
general formula:

40 wherein the benzene nuclei may be substi-
tuted or not and 'x' stands for an organic or
inorganic acid radicle.

45 The new dyestuffs are yellow to orange-red
crystalline powders soluble in water with
light yellow to orange-red color. They dye
natural and artificial silk and cotton when

using tannin or other mordants, in beautiful
greenish yellow to reddish-orange shades of
good fastness to light.

The following examples will illustrate my
invention, all parts being by weight:

50 Example 1.—One part of 1.3.3-trimethyl-
2-methylene indoline (see Berichte der
Deutschen Chem. Gesellschaft, volume 23,
page 2630, volume 31, page 612 and page 614)
is dissolved in at least 1 part of acetic acid 55
anhydride and 2 parts of sodium nitrite are
gradually added with stirring. The solution
soon becomes intensely yellow colored,
which process may be accelerated by heating.
When the indoline has disappeared, the re-
action mass is run into water in order to de-
stroy the acetic acid anhydride, and the dyestuff
is salted out with sodium chloride and
zinc chloride, if necessary, with the addition
of sodium bisulfite, in order to destroy the 60
excess of sodium nitrite. The new dyestuff
has probably the formula:

75 It is a clear, greenish-yellow body, which
dyes natural and artificial silk and cotton
when using tannin or other mordants, in
beautiful greenish-yellow shades of good
fastness to light, to acids and to alkalies.
Instead of sodium nitrite for example, amyl
nitrite can be employed; the reaction can also
be carried out in the presence of a solvent.

80 Example 2.—1 part of 5-amido-1.3.3-tri-
methyl-2-methylene indoline are mixed with
1 part of powdered dry sodium nitrite and
the mixture is slowly brought into 2 parts of
acetic acid anhydride while stirring. Stir-
ring is continued until the indoline has dis-
appeared, then the reaction mass is run into
water and the dyestuff, which dissolves in 85
90

water with yellow-red color is salted out. It corresponds probably to the formula:

10 wherein *x* stands for an organic or inorganic acid radical.

It is in a dry state an orange-red crystalline powder, easily soluble in water and diluted acids. It dyes natural and artificial silk and 15 cotton when using tannin as mordant in reddish-yellow shades of quite good fastness to light.

I wish it to be understood that in the following claims one may use instead of a salt 20 of the nitrous acid also an ester of the nitrous acid, and instead of a 1.3.3-trialkyl-2-methylene indoline a salt thereof.

I claim:

25 1. The process which consists in reacting with a salt of nitrous acid upon a 1.3.3-trialkyl-2-methylene indoline of the general formula:

35 wherein the benzene nucleus may be substituted in the presence of acetic acid anhydride.

2. The process which consists in reacting with sodium nitrite upon 5-amino-1.3.3-tri- 40 methyl-2-methylene indoline of the probable formula:

in the presence of acetic acid anhydride.

3. As new products dyestuffs corresponding 50 probably to the general formula:

wherein the benzene nuclei may be substituted or not and *x* stands for an organic or 55 inorganic acid radicle, which are in a dry state yellow to orange-red crystalline powders, soluble in water with light yellow to 60 orange-red color, and which dye natural and artificial silk and cotton when using tannin or other mordants in beautiful greenish- 65

yellow to reddish-yellow shades of good fastness to light.

4. As new products the dyestuffs corresponding 75 probably to the general formula:

wherein *x* stands for an organic or inorganic acid radicle and wherein the benzene nuclei may be substituted, said products being in the dry state yellow to orange-red crystalline powders, soluble in water with light yellow to 85 orange-red color, and which dye natural and artificial silk and cotton, when using tannin or other mordants, beautiful greenish-yellow to reddish-yellow shades of good fastness to light.

5. As a new product a dyestuff corresponding 90 probably to the general formula:

wherein *x* stands for an organic or inorganic acid radicle, which is in a dry state an orange-red crystalline powder, easily soluble in water and diluted acids, and which dyes natural and artificial silk and cotton when using tannin as a mordant in reddish-yellow shades of quite good fastness to light.

In testimony whereof I affix my signature. 110
